CLAIM

The ornamental design for an electroencephalographical (EEG) logger, as shown and described.

DESCRIPTION

1. Electroencephalographical (EEG) logger

1.1 : Top

1.2 : Front

1.3 : Back

1.4 : Left

1.5 : Right

1.6 : Bottom

1.7 : Perspective view bottom

1.8 : Perspective view top

The broken lines in the drawings depict portions of the electroencephalographical (EEG) logger that form no part of the claimed design.
